(57) **CLAIM**

The ornamental design for furniture module, as shown and described.

DESCRIPTION

FIG. 1 is a front elevation view of a first embodiment of a furniture module, according to the present invention; FIG. 2 is a left side elevation view thereof; FIG. 3 is a rear elevation view thereof; FIG. 4 is a top plan view thereof; FIG. 5 is a top, front, and right side perspective view thereof; FIG. 6 is a top, rear, and left side perspective view thereof; FIG. 7 is a front elevation view of a second embodiment of the furniture module, according to the present invention; FIG. 8 is a left side elevation view thereof; FIG. 9 is a rear elevation view thereof; FIG. 10 is a top plan view thereof; FIG. 11 is a top, front, and right side perspective view thereof; and, FIG. 12 is a top, rear, and left side perspective view thereof. In all the above figures the bottom view is not shown and is not claimed. The broken line showing of the furniture module is for the purpose of illustrating portions of the article and forms no part of the claimed design.
